UNITED STATES PATENT OFFICE

157,233

GLOVE HOLDING ATTACHMENT FOR
HANDBAGSGertrude Bloom and Israel Bloom,
New York, N. Y.

Application September 22, 1949, Serial No. 5,130

Term of patent 14 years

(Cl. D87—2)

To all whom it may concern:

Be it known that we, Gertrude Bloom and Israel Bloom, citizens of the United States, residing at New York city, county and State of New York, have invented a new, original, and ornamental Design for a Glove Holding Attachment for Handbags, of which the following is a specification, reference being had to the accompanying drawing, forming part thereof.

We claim:

The ornamental design for a glove holding attachment for handbags, substantially as shown.

GERTRUDE BLOOM.
ISRAEL BLOOM.
